(57) **CLAIM**

The ornamental design for a handle, as shown and described.

DESCRIPTION

FIG. 1 is a perspective view of a handle of the new design; FIG. 2 is a left side elevational view of the handle of FIG. 1, the right side being a mirror image;

FIG. 3 is a front elevational view of the handle of FIG. 1;

FIG. 4 is a rear elevational view of the handle of FIG. 1;

FIG. 5 is a top plan view of the handle of FIG. 1; and,

FIG. 6 is a bottom plan view of the handle of FIG. 1.

The broken line showings in the drawings are for illustrative purposes only and form no part of the claimed design.
